UNITED STATES PATENT OFFICE.

WILLIAM ARTHUR COLLINS, OF CHICAGO, ILLINOIS.

DEFORMED REINFORCING-BAR FOR CONCRETE.

1,016,984.

Specification of Letters Patent. Patented Feb. 13, 1912.

Application filed September 7, 1909. Serial No. 516,580.

To all whom it may concern:

Be it known that I, WILLIAM A. COLLINS, a citizen of the United States, and a resident of the city of Chicago, in the county 5 of Cook and State of Illinois, have invented certain new and useful Improvements in Deformed Reinforcing-Bars for Concrete; and I do hereby declare that the following is a full, clear, and exact description of the 10 same, reference being had to the accompanying drawings, and to the letters of reference marked thereon, which form a part of this specification.

My invention relates to certain improvements in deformed reinforcing bars for concrete, as will be hereinafter more definitely pointed out and claimed, reference being had to the accompanying drawing, in which:—

Figure 1 illustrates a round bar embodying my invention. Fig. 2 is a similar view at right angles with Fig. 1. Fig. 3 is a section taken on line 4—4 of Fig. 2.

As shown in the drawings: the figures illustrate a round bar embodying my invention. Said bar 1, is provided with bonding projections or lugs 2, arranged in pairs staggered for the length of the bar, each of said pairs being equal in length to the semi-circumference of the bar. Each pair 25 of projections or lugs 2 is spaced apart to provide a central bonding key or space 3, provided with abrupt shoulders 4—5, and one or more bonding spaces 6, of less depth than the key 3, may be provided, if desired. 30 In the construction shown, the concrete 35 firmly bonds in the key 3, and, owing to

the abrupt shoulders 4 or 5, the concrete prevents slippage and affords a very rigid construction. If desired the lugs or projections 2 may be divided into more than 40 two sections, and in any event the bar is not weakened as the keys are provided in the lugs only. The diagonally or diametrically opposite abrupt shoulders 14 or 15, afford excellent bonding faces and serve 45 to rigidly anchor the bars in the concrete.

Of course, any shape or size bar may be employed and various details of construction may be varied without departing from the principles of this invention, and I therefore do not desire to limit myself otherwise than necessitated by the prior art.

I claim as my invention:

A reinforcing bar or rod having a series of transverse projections or lugs arranged 55 in groups that are oppositely disposed on said bar, the members of said groups being extended each half-way around said bar or rod and being of even height throughout, and in staggered relation transversely with respect to each other and alternately disposed, the members of each of said groups being in alinement longitudinally of said bar or rod and being provided with bonding spaces.

In testimony whereof I have hereunto subscribed my name in the presence of two subscribing witnesses.

WILLIAM ARTHUR COLLINS.
